UNITED STATES PATENT OFFICE.

MILTON D. MESEROLE, OF MILFORD, CONNECTICUT, ASSIGNOR TO THE HAYES-MESEROLE MANUFACTURING CO., INC., OF MILFORD, CONNECTICUT, A CORPORATION OF CONNECTICUT.

HAIR CURLER.

Application filed July 12, 1924. Serial No. 725,579.

Fig. 1 is a face view of a hair curler embodying the features of this invention; Fig. 2 is a side view thereof; Fig. 3 is a view of the curler of Figs. 1 and 2 with the hair wound thereon; Fig. 4 is a view of the same structure with the hair secured to the curler. Fig. 5 is a face view of a modification of which Fig. 6 is a side view; Fig. 7 is a face view of a second modification of which Fig. 8 is a side view.

This invention relates particularly to a device for curling bobbed hair and has as its special feature a tongue or arm for holding the ends of the hair which is to be formed into a curl and a plurality of legs or wings which are capable of being bent against the hair after the curl is wound on the curler to keep it from unwinding. The curler is made preferably from pliable wire which has a coating of rubber and a braided covering. This material is much like the ordinary wire used in electric wiring, excepting that the metal core therein is made of iron or other cheap alloy instead of copper. The outer braided covering which is rough provides a surface which will readily hold the hair and avoid slipping.

In the drawings 1 indicates the hair curler which is made of a flexible material 2 comprised of the above described wire (an internal metal core with a rubber coating and a braided fabric covering). The body 3 of the curler is provided with the bifurcated legs 4 and 4^a, which are made continuous of the body. The legs 4, 4^a comprise one end of the curler extending to one side of the body 3 and the opposite end 5 extending oppositely to the legs 4 and 4^a. The body 3 is provided with a tongue or arm 6 and preferably is comprised of a separate piece of flexible wire 2 which is secured to the body 3 by means of the staple 7, which has its main portion around the body 3 and its ends compressed tightly around the legs 4 and 4^a. This staple is preferably located nearer the end 5 of the curler than toward the ends of the legs 4 and 4^a. In curling the hair the end of the hair is laid on the body 3 of the curler and the tongue or arm 6 is pressed down upon the hair so that it is held between the body 3 and the tongue or arm 6. The curler is then turned so as to roll the hair over the tongue or arm and body as illustrated in Fig. 3. The hair,

after a sufficient amount thereof has been rolled on the curler, is then secured to the curler and from unwinding by bending the ends 4 and 4^a of the legs against the hair as illustrated in Fig. 4. The end 5 may also be bent over the hair to hold it tightly on the curler and to keep the hair which is wound over the tongue or arm 6 from slipping off the end 5. The legs 4, 4^a may be bent to any position over the hair and if it is desirous may be bent so as to cross one another and twisted. The hair on the curler is held in the exact position in which the operator lays it during curling and is held against displacement at one end by the legs 4, 4^a and at the other end by the end 5.

Figs. 5 and 6 represent a modification of the structure to the extent that the entire curler is made from a single piece of flexible wire 2, which is bent at 8 and again at the point of the tongue or arm 6 in order to form one loop of the tongue or arm and again at 9 to form the other loop of the tongue or arm 6 and the leg 4^a. Figs. 7 and 8 represent a further modification of the device in which the curler is made from two like pieces of flexible wire 2 and the tongue or arm 6^a is made from a piece of flexible sheet metal, the staple 7 being made integral therewith. In this modification the rear portion 5 forms the separate legs 5 and 5^a alike to forward legs 4 and 4^a.

The main feature of this invention consists in forming a device with the separated legs or wings from a flexible material. The legs constitute means by which the operator may hold and turn the curler during the operation of winding the hair upon the curler. These legs are bent backwardly over the body of the curler to engage the hair after it is fully wound.

The users of curlers desire a range of adjustment of the device in order to produce a greater or less degree of wave of the hair and for this purpose the structure of this invention has been found satisfactory.

What I claim is:

A unitary hair curler comprising a solid body, a tongue, a plurality of legs, a rear end constituting a continuation of the legs, said body, legs and rear end being normally in the same plane, and the tongue lying normally substantially parallel to the body and leg portions and secured to the body inside

of the ends thereof and to one side of the transverse center line thereof; said body, tongue and ends being made of fabric covered flexible material and being bendable 5 in all directions, fastening means fixing one end of the tongue to the body and forming with the body means to hold the end of the hair between them, the middle portion of the tongue being covered by the hair as

winding proceeds and the extreme end of 10 the tongue during the winding of the hair projecting freely beyond the curled hair and affording means to depress the tongue in order to retain the end of the hair between said tongue and the body thereof. 15

In testimony whereof I have hereunto set my hand.

MILTON D. MESEROLE.
